US0D1104869S

(12) **United States Design Patent** (10) **Patent No.:** **US D1,104,869 S**
(45) **Date of Patent:** **** Dec. 9, 2025**

(54) **MOTORCYCLE**

(71) Applicant: **BOMBARDIER RECREATIONAL PRODUCTS INC.**, Valcourt (CA)

(72) Inventor: **Sebastian Martinez**, Bromont (CA)

(73) Assignee: **BOMBARDIER RECREATIONAL PRODUCTS INC.**, Valcourt (CA)

(**) Term: **15 Years**

(21) Appl. No.: **29/970,273**

(22) Filed: **Oct. 28, 2024**

Related U.S. Application Data

(62) Division of application No. 29/848,683, filed on Aug. 4, 2022, now Pat. No. Des. 1,054,324.
